ION CONTROLLER

William Wesley Hicks, San Francisco, Calif., assignor to Ionics, Inc., San Francisco, Calif., a corporation of California

Application January 11, 1949, Serial No. 70,277

6 Claims. (Cl. 250—86)

1

This invention relates to a device for selectively discharging positive or negative ions to the atmosphere within an enclosed area such as a dwelling or a room. Particularly this invention relates to low voltage no pressure ion generators, such as electric space heaters, which may be provided with means for selectively filtering out positive or negative ions, and which circulates those ions not filtered out throughout the desired area.

The presence of ions in a given space may result not only from natural ionization processes but also from the introduction of ions produced by the action of electric fields or by thermionic emission or in other ways. Of the foregoing I am interested particularly in thermionic emission and natural ionization processes.

I have observed that an ion filter is effective in controlling ions. Positive or negative ions can be discharged and eliminated by collecting them on a metal grid which has an electrical charge sufficient to attract the ion of opposite polarity.

I have found that a conventional electric air or space heater such as is disclosed in United States Letters Patent No. 1,704,479 produces electrons or ions by thermionic emission in sufficient quantity to be measured and in sufficient quantity to be of value as will presently be described.

Natural ionization processes may be best described as follows: Forces which tend to form these ions in the atmosphere are varied in their nature. A small number may be formed by the photoelectric effect, some ionization is produced by cosmic radiation, but probably the largest single factor in producing ions is the radioactive matter present in the soil. While the quantity of radioactive matter is small it is very widely distributed and so produces ions near the surface of the earth and in the pores of the soil from which it is withdrawn by the so-called respiration of the soil.

Therefore in a given atmosphere within a closed chamber, such as a room, there will exist in a free state a number of ions of both signs, although in all probability the positive will outnumber the negative. If, in the given room, there is also a heated metal surface such as previously referred to herein, there will be a further increase in the number of ions in the atmosphere therein.

Given this condition, I have considered the effects of these ions upon a person in the room. I have found, for example, that negative ions in most cases, produce a feeling of exhilaration while positive ions produce the opposite effect, it

2

being appreciated, of course, that some exceptions to the foregoing exist, depending upon the individual being tested. It has been found for example, that positive ions increase the rate of respiration, while a preponderance of negative ions causes patients to breathe more quietly. Specifically ionized air has been found to have beneficial therapeutic effects upon persons suffering from high blood pressure, rheumatism, 10 gout, neuritis and neuralgia, acute and chronic bronchitis, cardial and bronchial asthma and heart and arterial diseases.

Therefore, in addition to the common ventilating problems of properly heating, cleaning and 15 humidifying the air, there has been added the problem of providing proper ion concentration, either positive or negative. The problem which I have overcome, after ascertaining the biological effects of various concentrations of positive or 20 negative ions in the room atmosphere, has been to devise simple and inexpensive means of producing ions and changing the proportion of positive and negative ions in a given room.

It is an object of this invention to provide an 25 ion controller suitable for use in connection with an atmospheric electric air heater or other low voltage no pressure thermal means for producing ions at atmospheric pressure and for changing the proportion of positive and negative ions in a given chamber.

30 Further objects and advantages of the present invention will appear from the following description taken in conjunction with the accompanying drawing in which:

Figure 1 illustrates a conventional electric 35 heater incorporating my invention; and

Figure 2 illustrates a modification of the device shown in Figure 1.

As shown in Figure 1 I have provided a suitable low voltage no pressure ion generator in 40 the form of an electric heater such as is disclosed and described in the United States Letters Patent No. 1,704,479. An electric heater of this type is particularly advantageous inasmuch as the same, in addition to providing a heating medium, will also cause circulation of the air within a closed chamber or room. As shown in 45 the drawing the particular form of air heater disclosed is provided with a housing 10 which may be constructed of sheet metal or other suitable material and forms a support for the remainder of the device. Arranged within the housing 10 and supported from the inner walls of the same, is a hollow ceramic core 11, which is preferably tubular in shape to provide a central flue 12, the outer surface of which is adapted

to accommodate a resistance or heating element 13. The heating element 13 is connected to a suitable source of electric current as shown. A thermostat 14 may be placed in the circuit and is adapted to be actuated by the air entering the heater to open or close the circuit supplying electric current to the heater. A suitable switch 16 for the operation of the heater may also be provided.

The heater described offers heated surfaces 11 and 13 for the thermionic emission of ions. In addition, by virtue of its construction, it also circulates the air within the room, which air, it will be recalled, also contains ions. In this manner this heater is adapted to supply both positive and negative ions and to cause circulation of those and others throughout a room.

In order to regulate the circulation of ions through the room, as either positive or negative ions, I have provided a suitable means for selectively filtering out either positive or negative ions produced by the thermionic emitting surfaces 11 and 13 and residing in the air circulated through the heater. As shown, this means consists of a suitable grid 17, in the form of a simple nickel screen surrounding the heated elements, to which there is supplied a positive or negative charge depending, of course, upon the sign or charge of the ion which is to be collected or filtered out of the air stream. The charge to the grid 17 may be supplied from any suitable source such as a source of direct current, or through copper oxide rectifiers 18, as shown, connected with the usual source of power supplied to the heating element 13, it being important only that the same must be susceptible of selection, that is, that either a negative or positive charge must be available to an operator for application to the grid 17.

If the grid 17 is negatively charged it will attract positive ions, yet permit negative ions to pass therethrough in the air stream. Contrariwise, if the grid 17 is positively charged it will attract the negative ions and remove them from the air stream permitting the positive ions to circulate in the room. In this manner the sign of the ions circulating within the room may be controlled with the resultant therapeutic effects previously described.

The quantity of ions of a given sign produced and circulated by the device described herein is a function of the heat of the ion emitting surfaces, the volume and velocity of the air passed thereover, the charge applied to the grid, and the distance of the grid from the emitting surface.

Satisfactory results have been obtained under the following conditions. A low voltage, in some tests a negative voltage of 48 volts or less have been used, is supplied to the grid 17, and the grid 17 is formed of $\frac{1}{8}$ inch mesh nickel wire screen placed about $\frac{1}{8}$ of an inch from the heating surfaces 11 and 13. The voltage supplied to the element 13 has been of the order of 120 A. C. and the heating surfaces 11 and 13 have reached approximately 1000° F. The volume of air circulated has been approximately 5 cubic feet per minute at about 200 feet per minute velocity. Ions of one sign have been filtered out of the air stream and ions of the opposite sign have been circulated throughout the room with beneficial therapeutic effects.

In the modification as shown in Figure 2 I have inserted in place of the conventional electric heater illustrated, a filament 21, which acts as a thermionic emitter. The filament may be suspended in any conventional manner in a

housing 22 which, as shown, consists of a duct or tube, at one end of which I have provided a fan or blower 23 and at the other or discharge end of which I have provided a grid 24.

5 The filament 21 is preferably made of platinum. It will be observed that this filament, while acting as a thermionic emitter, does not produce the quantity of heat produced by the device illustrated in Figure 1, although, because of the high temperature, (in the neighborhood of 2,500° F.) it produces substantially the same quantity of ions.

10 It will be recalled that because of its construction, the device illustrated in Figure 1 also acted to circulate throughout the room the ions produced by the resistance element and the ions in the air. Because of the fact that the device shown in Figure 2 does not produce the same quantity of heat, it is necessary that it be provided with a fan which will provide forced circulation through the member 22 and over the filament 21 thereby forcing the ions carried by the air through the grid 24 which is charged in the same manner as the grid 17 previously described.

15 In all other respects the device shown in Figure 2 operates in the same manner as the device illustrated in Figure 1, the principal difference being that the thermionic emitter illustrated in Figure 1, because of its construction, acts as a circulating member whereas the filament 21 shown in Figure 2 does not. The addition of the fan 23 provides the circulation required.

20 I claim:

1. In a device for controlling the ion concentration in a room in atmospheric air at atmospheric pressure, means for producing ions of both signs in a predetermined zone in atmosphere, charged grid means for selectively collecting at atmospheric pressure ions of the sign opposite to the sign of the grid, and means for passing a stream of air first through said zone and then through said grid to carry a substantial number of said ions to said grid, whereby the ions of the same sign as the grid will be carried therethrough and the ions of the sign opposite to the sign of the grid will be collected by said grid, said grid being positioned to extend across the path of air moving in said stream.

2. In a device for controlling the ion concentration in a room in atmospheric air at atmospheric pressure, thermal means for producing ions of both signs in a predetermined zone in atmosphere, charged grid means for selectively collecting at atmospheric pressure ions of the sign opposite to the sign of the grid, and means for passing a stream of air first through said zone and then through said grid to carry a substantial number of said ions to said grid, whereby the ions of the same sign as the grid will be carried therethrough and the ions of the sign opposite to the sign of the grid will be collected by said grid, said grid being positioned to extend across the path of air moving in said stream.

3. In a device for controlling the ion concentration in a room in atmospheric air at atmospheric pressure, means for producing ions of both signs in a predetermined zone in atmosphere, charged grid means surrounding said means for producing ions for selectively collecting at atmospheric pressure ions of the sign opposite to the sign of the grid, and means for passing a stream of air first through said zone and then through said grid to carry a substantial number of said

ions to said grid, whereby the ions of the same sign as the grid will be carried therethrough and the ions of the sign opposite to the sign of the grid will be collected by said grid, said grid being positioned to extend across the path of air moving in said stream.

4. In a device for controlling the ion concentration in a room in atmospheric air at atmospheric pressure, thermal means comprising an electric resistance element for producing ions of both signs in a predetermined zone in atmosphere, charged grid means surrounding said means for producing ions for selectively collecting at atmospheric pressure ions of the sign opposite to the sign of the grid, and means for passing a stream of air first through said zone and then through said grid to carry a substantial number of said ions to said grid, whereby the ions of the same sign as the grid will be carried therethrough and the ions of the sign opposite to the sign of the grid will be collected by said grid, said grid being positioned to extend across the path of air moving in said stream.

5. In a device for controlling the negative ion concentration in a room in atmospheric air at atmospheric pressure, thermionic means comprising an electric resistance element for producing ions of both signs in a predetermined zone adjacent said thermionic means, a negatively charged grid surrounding said thermionic means and lying beyond said zone for selectively collecting positive ions, said thermionic means and said grid defining an electrostatic field, and

means for passing a stream of air first through said zone and said field and then through said grid whereby the ions formed in said zone will be carried to said grid, and the negative ions will be carried therethrough and the positive ions will be collected thereby.

6. A method of controlling the ion concentration in a room at atmospheric pressure and in atmospheric air, comprising the steps of producing ions of both signs from the same source in a predetermined zone, inducing a current of air through said zone to carry the ions so produced through a second zone, and establishing an electrostatic field having one terminus in said second zone whereby ions of one sign will be collected in said second zone and ions of the other sign will be carried therethrough.
